US0D1048945S

(12) **United States Design Patent** (10) Patent No.: **US D1,048,945 S**
 Sun et al. (45) Date of Patent: ** Oct. 29, 2024

(54) **ELECTRIC MOTOR SCOOTER**

(71) Applicants: **Tailg Science and Technology Inc., Ltd.**, Wuxi (CN); **Tailg Science and Technology (Jiangsu) Inc., Ltd.**, Wuxi (CN)

(72) Inventors: **Muchu Sun**, Wuxi (CN); **Lanmei Zuo**, Wuxi (CN)

(73) Assignee: **Tailg Science and Technology (Dongguan) Co., Ltd.**, Dongguan (CN)

(**) Term: **15 Years**

(21) Appl. No.: **29/886,244**

(22) Filed: **Mar. 7, 2023**

(30) **Foreign Application Priority Data**

Sep. 22, 2022 (CN) 202230628020.9

(57) **CLAIM**

The ornamental design for an electric motor scooter as shown and described.

DESCRIPTION

FIG. 1 is a front and left side perspective view of an electric motor scooter embodying our new design;
 FIG. 2 is a left side elevation view thereof;
 FIG. 3 is a right side elevation view thereof;
 FIG. 4 is a front elevation view thereof;
 FIG. 5 is a rear elevation view thereof;
 FIG. 6 is a top view thereof; and,
 FIG. 7 is a bottom plan view thereof.
